DESIGN FOR A HOLDER OR SIMILAR ARTICLE FOR A PERFUME BOTTLE

Henry Samuels Graff, New York, N. Y.

Application July 29, 1940, Serial No. 94,009

Term of patent 7 years

To all whom it may concern:

Be it known that I, Henry Samuels Graff, a citizen of the United States, residing in New York city, in the county of New York and State of New York, have invented a new, original, and ornamental Design for a Holder or Similar Article for a Perfume Bottle, of which the following is a specification, reference being had to the accompanying drawing, forming part thereof.

Fig. 1 is a side elevational view of a holder or similar article for a perfume bottle showing my new design;

Fig. 2 is a plan view; and

Fig. 3 is a perspective view showing the top portion removed from the base portion.

I claim:

The ornamental design for a holder or similar article for a perfume bottle, substantially as shown.

HENRY SAMUELS GRAFF.
